UNITED STATES PATENT OFFICE.

JOHN S. BUHRER, OF CHICAGO, ILLINOIS.

DESIGN FOR A DOOR-HANGER.

SPECIFICATION forming part of Design No. 16,179, dated July 21, 1885.

Application filed April 13, 1885. Term of patent 14 years.

To all whom it may concern:

Be it known that I, JOHN S. BUHRER, residing at Chicago, in the county of Cook and State of Illinois, and a citizen of the United States, 5 have invented and produced a new and original Design for Door-Hangers, of which the following is a full description, reference being had to the accompanying drawings, in which—

Figures 1 and 2 are side elevations, respectively showing the novel feature of the design in reversed positions.

The leading feature of the present design is the configuration of a horseshoe forming the pendent or depending portion of the carriage 15 or frame of a door-hanger. The design will be hereinafter specifically described, and pointed out in the claim.

A is the horseshoe or lower portion of the

design, and B the portion from which the horseshoe portion is produced, either as shown in 20 Fig. 1 or as shown in Fig. 2, to form in outline a yoke or magnet shaped portion, while the lower portion forms in outline a horseshoe shape. The outline produced by the shoe is a unique and ornamental one in use, and the 25 combined outline of the horseshoe and yoke is very tasteful and effective in appearance.

I claim—

The design for a door-hanger herein shown and described, consisting of a horseshoe shape 30 for the lower or depending portion and a yoke shape for the upper portion.

JOHN S. BUHRER.

Witnesses:

ALBERT H. ADAMS,
O. W. BOND.
